LOUIS HARTUNG, JR., OF KEARNY, NEW JERSEY

BOILER

Application filed July 11, 1929. Serial No. 377,527.

The invention relates to improvements in boilers and particularly to low pressure boilers for steam or hot water heating furnaces.

The type of boiler in common use at the present time for steam and hot water heating is the sectional cast iron boiler. Boilers of this style have numerous disadvantages. Due to the thickness of the walls of the water chambers, this being made necessary on account of casting, a substantial amount of heat is absorbed by these walls and wasted before the water reaches its boiling point. This naturally results in an increased consumption of fuel. Due to the heavy wall construction, considerable time must elapse before heat can be produced, particularly when the boiler is cold. In extremely cold weather after the fire has been forced and a head of steam raised, the furnace must be attended to at short intervals of time to maintain the pressure. This is both annoying and costly as to fuel consumption.

If the water is not watched carefully in a cast iron boiler, and becomes too low, the entire boiler or one of its sections is soon ruined. It is well known that it is expensive and consumes a substantial amount of time to renew one of the sections in a cast iron boiler.

The object of the present invention is to provide a low pressure boiler that will overcome the foregoing faults and have other additional advantages.

In accordance with the invention a casing is provided and a heating unit removably mounted in the casing. The heating unit comprises upper and lower drums, connected by a plurality of riser tubes. One of the most important features of the invention is that all joints or connections between the riser tubes and the drums are welded.

This construction permits of numerous advantages. The tubes and drums may be of extremely light section as compared to the section of a cast iron boiler. Thus the water may be heated to a boiling point very rapidly. After the water has reached the boiling point, the fire may be banked and the water will be kept sufficiently hot to maintain the desired heat. Thus a great saving

of fuel will be effected and the bother of attending to the furnace at short intervals will be eliminated.

With the welded construction all nuts and threaded connections are done away with. As a matter of fact, due to the expansion and contraction of the drums and tubes, it would be highly impractical if not impossible to use threaded connections.

Due to its lightness in weight and ease of assembling a boiler or furnace of this nature, it may be quickly and economically installed.

A further decided advantage resides in the fact that the heating unit may be easily and rapidly removed from its casing. This is particularly useful if the heating unit becomes worn and it is desired to install a new one, or if it is necessary to make repairs to any part of the unit. If a leak develops or it becomes necessary to repair any part, it may be repaired quickly and with a great deal less expense than in the cast iron boiler, where it is necessary to remove and replace a complete section.

The boiler being made entirely of tubing, great strength is obtained. Even if a person should become careless and allow the water to fall too low, little harm will be done as compared to the cast iron boiler.

The water tube boiler of the present invention is particularly adapted for excellent water circulation and rapid heat transmission.

Other objects and advantages will become apparent as this specification proceeds. Referring to the drawings forming a part thereof and in which a preferred form of the invention is illustrated;

Fig. 1 is a cross sectional view taken on line 1-1 of Fig. 2;

Fig. 2 is a central longitudinal sectional view;

Fig. 3 is a sectional plan view taken on the broken line 3-3 of Fig. 1;

Fig. 4 is an end view of the heating unit removed from its casing; and

Fig. 5 is a side elevation of the heating unit.

Referring again to the drawings, the side

walls of the casing are designated by the reference numeral 10 and the front and rear walls by the numerals 12 and 13 respectively. The casing may be made of boiler plate or 5 other suitable material and is secured to a flange on a base 14 by angles and bolts. The front and end walls 12 and 13 are secured in place in any suitable manner. As indicated in Figs. 2 and 3 angle irons and bolts are 10 utilized for this purpose in addition to flanges on the front and rear of the base 14.

In the preferred embodiment of the invention illustrated in the drawings, the base 14 has an inner peripheral flange 15 for 15 supporting the heating unit hereinafter described. Formed on side walls of the base 14 below the flange 15 is a channel 16 in which the grates 17 are mounted. The area below the grates forms the ashpit of the 20 furnace. It will be understood that the grates are provided with the usual form of shaker handle and operating connections from said handle to the grates. As such constructions are well known it is not thought 25 necessary to illustrate same.

The front wall of the base is provided with the usual ashpit door 18 and the front wall of the casing has a fire door 19 and cleanout door 20. If oil were being used for fuel 30 instead of coal, naturally the grates would be removed. The upper part of the rear wall is provided with the usual discharge 21 to the chimney or stack. The details of construction, shape and arrangement of parts 35 of the casing and its base may be widely varied.

The heating unit comprises an upper drum or header 25. Its ends 26 are slabbed off as indicated in Figs. 2 and 5. The ends 40 26 are formed of plates which are welded at 27 to the drum 25. The slabbed off ends permit of a free passage of the heat in that the space between the upper part of the header and the end walls is substantially increased. The lower part of the header extends substantially the length of the furnace 45 and allows ample room for a large number of riser tubes and thus provides an increased heating surface.

50 The header 25 has a plurality of outlets from its upper side. The connection 28 may lead to the safety valve and gauge glass and connections 29 may lead to the radiators or apparatus which is to be supplied with steam. Any suitable number of connections 55 29 may be provided depending upon the size of the heating plant. The outlets 28 and 29 are provided with couplings 30 which are loosened when it is desired to remove 60 the heating unit from the casing.

The lower drum 31 of the heating unit is 65 of smaller diameter. It rests adjacent the side and end walls of the furnace and is supported on the flange 15 of the base 14. In the form illustrated in the drawings this

lower drum is rectangular and surrounds the fire lip of the furnace. It may be constructed of four lengths of pipe, each length being mitered at ends and the mitered joints welded at 31^a. The flange 15 supports it 70 above the grates and thus substantially its whole area is exposed in the active heat zone of the furnace. If desired, the flange 15 need not be continuous.

The forward part of the lower drum 31 75 may be provided with removable cleanout plugs 32 and the rear part with connections 33. One of the connections 33 may lead from the water supply and the other from the heating system.

80 The upper drum 25 and the side portions of the lower drum 31 are connected by a plurality of riser tubes. As illustrated, there are two rows 34 and 35 of these tubes on either side of the heating unit. These tubes 85 are welded at 36 to the upper drum and at 37 to the lower drum. The tubes in each row are staggered in relation to each other. It is important to have the riser tubes connected to the lower part of the drum 25 90 so as to insure their ends being covered with water. The foregoing arrangement of riser tubes provides a maximum number of tubes in the most efficient heating area of the furnace.

95 In order to greatly increase the heating surface auxiliary headers 38 are positioned at the front and rear of the heating unit. The end closures of the auxiliary headers are welded to the ends of the headers at 100 38^a. These auxiliary headers are connected to the upper drum 25 by short riser tubes 39 welded at 40 to the headers 38 and at 41 to the drum 25. A pair of riser tubes 42 connect the front auxiliary header 38 with 105 the forward part of the lower header 31 and are welded at 43 to the auxiliary header and lower drum. The riser tubes 42 are spaced apart sufficiently to allow ample room for the fuel to be fed from the fire door 19. 110 The rear auxiliary header 38 is connected to the rear part of the drum 31 by a plurality of riser tubes 44 welded at 45 to the auxiliary header and lower drum. If oil 115 were being used for fuel, the arrangements of auxiliary headers and riser tubes might be alike at both ends.

From the foregoing it will be apparent that an efficient heating unit is provided and one in which all the connections or joints are welded. Either the front or rear walls 12 or 13 may be taken off and the entire heating unit easily and quickly removed from its casing.

120 Resting on angles 46 welded to the upper 125 drum and other angles 47 secured to the casing are removable baffle plates 48. The baffle plates 48 direct a substantial amount of the heat over the top of the drum 25 before leaving the discharge 21.

The inside of the casing and front and rear walls may be lined with asbestos 49 or other suitable heat insulating material.

It is preferable to use seamless tubing 5 throughout the construction of the heating unit. Due to the great strength of such tubing and its welded joints, an extremely light section of metal is permissible. Thus as the heat is generated in the fire box and passes 10 through the casing and heating unit the most efficient results are obtained. A great saving in fuel consumption is effected and considerable time and effort saved in caring for the furnace. Due to the greater factor 15 of safety over the cast iron boilers a lower rate of insurance also prevails.

Many changes in details of construction 20 and arrangements of parts may be made by one skilled in the art and all such changes are to be considered as coming within the 25 purview of the invention and the scope of the appended claims.

I claim:

1. A device of the character described having in combination, a substantially rectangular casing, and a heating unit removably mounted in said casing, said heating unit comprising an upper drum of substantially large diameter located in the upper part of 25 said casing, said upper drum having its ends slabbed off to substantially increase the space between the upper part of said upper drum and the end walls of said casing for the free 30 passage of the heat, and a lower drum of smaller diameter supported adjacent the 35 walls of said casing, said drums being connected by a plurality of riser tubes, all the connections between said riser tubes and said drums being welded.

2. A device of the character described having in combination, a substantially rectangular casing, a heating unit removably mounted in said casing, said heating unit comprising an upper drum of substantially large 40 diameter located in the upper part of said casing, said upper drum having its ends slabbed off to substantially increase the space between the upper part of said upper drum and the end walls of said casing for the free 45 passage of the heat, and a lower drum of smaller diameter supported adjacent the walls of said casing, said drums being connected by a plurality of riser tubes, all the connections between said riser tubes and said 50 drums being welded, and removable baffles between the sides of said upper drum and the side walls of said casing to direct the 55 heat over said upper drum.

3. A device of the character described having in combination a substantially rectangular casing, a base, supports on the walls of said base, and a heating unit removably mounted in said casing on said supports, said heating unit comprising a longitudinally 60 extending drum in the upper part of said

casing and another drum lying in proximity to the end walls and side walls of said casing at the lower part thereof, said lower drum having side portions and front and back portions, rows of riser tubes connecting 70 the side portions of said lower drum to said upper drum and auxiliary headers or drums at the front and rear of said heating unit, said auxiliary headers or drums having connections to said upper and lower drums, all 75 the joints in said heating unit being welded.

In testimony whereof I affix my signature.
